UNITED STATES PATENT OFFICE

171,360

PENDANT OR SIMILAR ARTICLE

James S. Lunn, Hempstead, N. Y.

Application April 16, 1953, Serial No. 24,531

Term of patent 14 years

(Cl. D45—17)

To all whom it may concern:

Be it known that I, James S. Lunn, a citizen of the United States of America, residing in Hempstead, county of Nassau, and State of New York, have invented a new, original, and ornamental Design for a Pendant or Similar Article, of which the following is a specification, reference being had to the accompanying drawing, forming part thereof.

Fig. 1 is a plan view of a pendant or similar article showing my new design.

Fig. 2 is an edge view thereof.

I claim:

The ornamental design for a pendant or similar article, substantially as shown.

JAMES S. LUNN.
